UNITED STATES PATENT OFFICE.

FREDRIK LJUNGSTRÖM, OF BREVIK, LIDINGON, AND ISIDOR BROBERG, OF SKARSATRA, LIDINGON, SWEDEN, ASSIGNORS TO AKTIEBOLAGET LJUNGSTRÖMS ANGTURBIN, OF STOCKHOLM, SWEDEN, A CORPORATION.

AIR-PREHEATER FOR LOCOMOTIVES AND THE LIKE.

1,360,546.

Specification of Letters Patent. Patented Nov. 30, 1920.

Application filed April 2, 1919. Serial No. 287,023.

To all whom it may concern:

Be it known that we, FREDRIK LJUNGSTRÖM, a subject of the King of Sweden, residing at Brevik, Lidingon, Sweden, and 5 ISIDOR BROBERG, a subject of the King of Sweden, residing at Tallhyddan, Skarsatra, Lidingon, Sweden, have invented certain new and useful Improvements in Air-Preheaters for Locomotives and the like, of 10 which the following is a specification.

The present invention relates to a special arrangement of air-preheater for locomotives, locomobiles etc. and has for its purpose to provide a fuel economizer wherein 15 the tubes are disposed so as to insure a rigid and simple construction capable of being effectively cleansed out by a suitable form of steam-sweeping device connected therewith.

To this end, the invention primarily consists therein; that the longitudinally disposed tubes of the preheater, which are placed partly, or wholly, in front of the boiler in such manner that sweeping and removal of the boiler tubes may be effected without 25 hindrance from the preheater, are arranged beneath the smoke box.

An embodiment of the invention is shown by way of example in the accompanying drawings, in which Figure 1 represents a 30 longitudinal section of the smoke box of a locomotive provided with a preheater according to the invention. Fig. 2 is a front view of the same partly in section, a preferable form of a steam blowing device for the 35 cleansing of the preheater tubes being shown in connection therewith. Fig. 3 shows an alternate form of the steam cleansing device.

Referring to the drawing, 1 is the smoke box of a locomotive, the same being divided 40 into two compartments 2 and 3 by means of a partition 4. The air-preheater which according to the invention is of rectangular shape, and comprises the pre-heater tubes 5, is disposed underneath the smoke box 1, as 45 will be seen from the drawing. The combustion gases issuing from the boiler tubes 6 into the compartment 3 of the smoke box 1 upon striking the partition 4 move downward past and along the tubes 5 of the preheater and thence upward into the compartment 2 of the smoke box from which the 50 gases are driven off through the smoke stack 7. The soot and coal-dust accumulating at the bottom of the preheater are removed

through the outtake 8. The air is forced 55 into the preheater tubes 5 by the air pressure caused by the forward movement of the locomotive, and it then passes through the tubes 5 and a duct 9 to the furnace of the boiler.

The form of tube cleansing device shown 60 in Fig. 2 of the drawing comprises a stop cock 9' in a steam supply pipe from which the branch conduits 10 lead the steam to four groups of steam pipes 11, which are provided with apertures on one or both sides 65 opposite the preheater tubes 5. The cleansing pipes being thus divided in a number of sets, only part of the preheater tubes need be swept at a time, as may be required.

The said cleansing device may be attached 70 to the front or the rear wall, or disposed in any suitable place of the preheater, or it may be movably arranged in the longitudinal direction of the preheater.

Where the preheater tubes need not be 75 swept by sets, the simpler form of cleansing device shown in Fig. 3 may be employed. In this embodiment the steam is conducted through a central pipe 12 to the horizontal branch pipes 13 projecting between the rows 80 of preheater tubes 5, the steam being forced out through apertures provided in the walls of said pipes 13 so as to sweep off the soot from the preheater tubes 5. It is evident, 85 that this form of cleansing device; too, may be either rigidly or movably arranged in the manner described with reference to Fig. 2.

What we claim as new and desire to secure by Letters Patent of the United States is:— 90

1. In locomotives or the like having a boiler and a smoke box, a preheater arranged longitudinally in front of the boiler and beneath the smoke box and consisting of a plurality of longitudinally disposed tubes. 95

2. A preheater as claimed in claim 1, provided with an accumulator of coal dust.

3. A preheater as claimed in claim 1, combined with a pipe-system provided with a number of holes and connected to a steam 100 supply, the said pipe-system being arranged in the longitudinal direction of the tubes.

4. A preheater as claimed in claim 1, having a rectangular shape transversely to the longitudinal direction of the boiler.

5. A preheater as claimed in claim 1, in combination with partitions, inserted in the smoke box and forcing the combustion gases 105

downward to the preheater, the said gases then moving along the preheater, and finally escaping upward into the smoke stack.

6. A preheater as claimed in claim 1, in combination with a pipe, situated below the tubes and connecting the preheater with the furnace.

In witness whereof we have hereunto set our hands in the presence of two witnesses.

FREDRIK LJUNGSTRÖM.
ISIDOR BROBERG.

Witnesses:

P. H. BERGROTH,
GRETA PRIM.
